CLAIM

The ornamental design for an electronic device with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of an electronic device with graphical user interface showing the claimed design;

FIG. 2 is a second embodiment thereof; and,

FIG. 3 is a front view of the first embodiment of FIG. 1, shown on an alternate electronic device. The graphical user interface design of FIG. 2 may be similarly applied thereto. The outer broken lines in the figures show an electronic device, and form no part of the claimed design. The remaining broken lines show portions of the graphical user interface that form no part of the claimed design.
